CLAIM

The ornamental design for an light emitting diode package, as shown and described.

DESCRIPTION

FIG. 1 is a top perspective view of a light emitting diode package showing our design according to one embodiment; FIG. 2 is a bottom perspective view thereof;

FIG. 3 is a first side view thereof;

FIG. 4 is a second side view thereof;

FIG. 5 is a third side view thereof;

FIG. 6 is a fourth side view thereof;

FIG. 7 is a top plan view thereof;

FIG. 8 is a bottom plan view thereof;

FIG. 9 is a top perspective view of a light emitting diode package showing our design according to second embodiment;

FIG. 10 is a bottom perspective view thereof;

FIG. 11 is a first side view thereof;

FIG. 12 is a second side view thereof;

FIG. 13 is a third side view thereof;

FIG. 14 is a fourth side view thereof;

FIG. 15 is a top plan view thereof; and,

FIG. 16 is a bottom plan view thereof.

The dash-dash broken lines in the drawing depict portions of the light emitting diode package and form no part of the claimed design.
